(21) Appl. No.: **29/633,962**

The ornamental design for a juicer with reversible lid, as shown and described.

(22) Filed: **Jan. 17, 2018**

(30) **Foreign Application Priority Data**

DESCRIPTION

Jul. 17, 2017 (EM) 004107217-0005

FIG. 1 is a side view of the juicer with reversible lid showing my new design.

(51) **LOC (11) Cl.** **07-04**

FIG. 2 is another side view thereof.

(52) **U.S. Cl.**

FIG. 3 is another side view thereof.

USPC **D7/667**

FIG. 4 is another side view thereof.

(58) **Field of Classification Search**

FIG. 5 is a top view thereof.

USPC D7/665, 666, 669, 368, 584, 586, 587

FIG. 6 is a bottom view thereof.

CPC A23N 1/00; A23N 1/003; A47G 19/30;

FIG. 7 is a top perspective view thereof.

..... A47J 19/02; A47J 19/022; A47J 43/14

FIG. 8 is a top perspective view thereof with the lid reversed.

See application file for complete search history.

FIG. 9 is a top perspective exploded view thereof; and,

FIG. 10 is a top perspective exploded view thereof with the lid reversed.

The broken lines in the drawings illustrate portions of the juicer with reversible lid which form no part of the claimed design.
